UNITED STATES PATENT OFFICE.

LOUIS STEINBERGER, OF NEW YORK, N. Y.

DISK STRAIN-INSULATOR.

No. 904,370.

Specification of Letters Patent.

Patented Nov. 17, 1908.

Application filed January 20, 1908. Serial No. 411,812.

To all whom it may concern:

Be it known that I, LOUIS STEINBERGER, a citizen of the United States, and a resident of the city of New York, borough of Brooklyn, in the county of Kings and State of New York, have invented a new and Improved Disk Strain-Insulator, of which the following is a full, clear, and exact description.

10 My invention relates to strain insulators, and particularly those of the disk type, my more especial object being to improve the general construction of such insulators and to render them, as near as practicable, proof 15 against the evil effects of moisture.

My invention further relates to increasing the dielectric properties of said insulators and giving them a high degree of mechanical strength.

20 Reference is to be had to the accompanying drawings forming a part of this specification, in which similar characters of reference indicate corresponding parts in all the figures.

25 Figure 1 is an end elevation of the disk insulator complete, this view showing the eye-bolt and also the various annular hoods used for enabling the insulator to shed moisture; Fig. 2 is an enlarged central elevation 30 through the insulator, on the line 2—2 in Fig. 1, showing the metallic parts and their relations to the insulating material, and also showing the location of the several steps and annular flanges of insulating material, forming 35 an integral part of the disk; Fig. 3 is an enlarged perspective view of one of the metallic tension members to be embedded within the insulating material, this tension member having the form of a frusto-conical collar.

40 and a bail formed integral therewith and adapted to be partially embedded within the insulating material; Fig. 4 is an end elevation 45 of the frusto-conical collar provided with a bottom having an opening and also having a slot merging into said opening to facilitate the entrance of a portion of an eye-bolt or other tension member into the frusto-conical collar; Fig. 5 is a side elevation 50 showing two of my improved disk strain insulators connected together for withstanding high potential; and Fig. 6 is a detail view showing a swivel joint for connecting together a plurality of the insulators for the purpose of increasing the dielectric strength 55 of the latter, and at the same time to provide flexibility to the structure, and to per-

mit one or more of the disks to be rotated to any desired extent relatively to others when required.

A bail 6 is provided with enlarged portions 7 and with a frusto-conical collar 8 having a bottom 9, all of these parts being integral. The collar 8 is provided with a slot 11, which extends through the bottom 9, and merges into the opening 10, as shown in Fig. 4. An eye-bolt 12 is provided with a stem 13 and with a conical head 14, these parts being integral. The eye-bolt may be partially inserted within the collar by passing the entire bolt into the bail 6, the eye-bolt 12 being caused to protrude through the slot 11. This slot may be made of considerable width, as shown, for the purpose of allowing the eye 12 to be made comparatively large. The form of the slot 11 can best be understood 75 by reference to Fig. 2, the collar 8 being so shaped internally as to form parallel sides for the slot, these parallel sides extending to the enlarged portions 7 of the bail. This form also affords an excellent anchorage for 80 the insulating material hereinafter described.

At 15 is a mass of insulating material provided with steps 16 of annular conformity, and further provided with an annular flange 18 separated from the steps by an annular 85 groove 17. A larger flange 20, also of annular form, is disposed adjacent to the flange 18 and separated therefrom by an annular groove 19. A disk 21 extends directly outward and at a right angle relatively to the 90 strain members. The disk, flanges and central body portion are preferably made from a single integral mass of insulating material.

The above description of the insulating material relates only to the right-hand side 95 of the same, as seen in Fig. 2. The left-hand side being of analogous conformity, it follows that the various flanges and steps are made in pairs, the members of each pair being disposed oppositely to, and integral with, 100 each other as will be understood from Fig. 2.

In assembling the insulator, the eye-bolt is so placed that the head 14 occupies the center of the collar 8 and the insulating material is forced into and around the head 14 so as to occupy the interior of the collar 8. The portions 7 of the bail 6 are thus embedded within the insulating material and owing to their form they are not easily dislodged therefrom.

110 The various steps 16 and pairs of hoods 18, 20 are formed by molding or pressing up the

plastic material in molds suitable for the purpose. With an insulator made as above described and mounted so that its general axis of suspension is horizontal, the pairs of flanges and the grooves separating the same serve to prevent the effective entrance of moisture in such manner as to destroy the dielectric qualities of the insulator. As may be seen from Fig. 2, it is impossible for rain to so thoroughly wet all parts of the insulator as to invite undue leakage of the electric current. If the rain flows into the insulator from the right-hand side, some parts of the annular flanges will remain dry. Similarly, if the rain beats in from the left-hand side, according to Fig. 2, some parts of the flanges will likewise remain dry. Unless the rain assumes unusual violence, it is difficult, if not impossible, for the moisture, due either to the spattering of rain drops, the lateral effect of the wind upon the rain, or the creeping of rain water from any cause, to totally destroy, or even to seriously impair, the insulating qualities of the device.

As indicated in Fig. 5, two insulators of the kind above described may be connected together. In Fig. 6 I show more in detail the construction of the swivel used in connecting the two insulators together. Clevises 22, 23 are connected by a stem 25 mounted integrally upon the clevis 23, this stem terminating in a head 24. Pins 26, 27 pass through the two clevises 22, 23 and serve to connect the latter with the insulators.

Owing to the novel design of my disk strain insulator, it will be readily observed that it affords a large interrupted insulating surface for the prevention of surface leakage, thereby providing a very large factor of safety. The form of the strain members and their disposition relatively to each other and to the insulating disk is such as to provide a strain insulator of exceptionally great mechanical strength, combined with the highest possible form of electrical insulation. These disk insulators may be used separately or a number of them may be linked or connected together in any preferred manner for supporting a line, dead ending, or in any other relation where currents of very high potential are employed.

I do not limit myself to the use of any prescribed materials, I prefer, however, to employ the insulating material well known in the art as "electrose". Nor do I limit myself to an insulator constructed exactly as shown, nor to the precise form of either of the separate portions. Neither do I limit myself to any particular combination of these parts, for the reason that variations may be made by those skilled in the art without departing from the spirit or scope of my invention.

Having thus described my invention, I

claim as new and desire to secure by Letters Patent:

1. An insulator comprising a collar provided with an opening and with slots merging into said opening, an eye-bolt provided with an eye adapted to pass through said slots and said opening, and further provided with a head, said head being disposed within said collar and concentric thereto, and a quantity of insulating material disposed intermediate said head and said collar.

2. An insulator, comprising a metallic member of frusto-conical form provided with a bottom, and further provided with an opening in said bottom and with slots in said bottom merging into said opening, a bolt provided with a stem extending through said opening, and further provided with a head extending into said collar, and a mass of insulating material disposed intermediate said head and said collar.

3. A disk insulator, comprising a metallic member of frusto-conical form provided with a bottom, and further provided with a slot extending practically the entire width of the bottom, said slot being provided with walls substantially parallel with each other and thus inclined relatively to the outer portion of said frusto-conical member, a bolt provided with a stem extending through said slot and further provided with a portion disposed inside of said frusto-conical member, and a mass of insulating material partially embedding said bolt, said mass of insulating material internally engaging said metallic member of frusto-conical form.

4. An insulator comprising a metallic collar of frusto-conical form provided with a bail, and further provided with a central opening and with a slot merging into said central opening, said slot being of great width and bounded by walls spaced apart by a distance representing practically the greatest inner diameter of said frusto-conical collar, a bolt extending through said central opening and provided with a portion concentric to said frusto-conical collar, said bolt being provided with a portion of proper size to pass through said slot, and insulating material disposed intermediate the enlarged portion of said bolt and said frusto-conical collar.

5. A disk strain insulator, comprising a pair of suspension members, and a mass of insulating material partially enveloping the same, said mass of insulating material being provided with pairs of flanges extending in opposite directions, the individual flanges of pairs overlapping.

6. A disk strain insulator, comprising a pair of metallic suspension members, and a mass of insulating material partially enveloping the same, said mass of insulating material being provided with flanges extending

in opposite directions, and further provided with a disk disposed intermediate said flanges and of greater diameter than the same.

7. A disk strain insulator, comprising a plurality of tension members, and a mass of insulating material partially enveloping the same, said insulating material being formed into flanges and also into steps.

8. A disk strain insulator, comprising suspension members, and a mass of insulating material partially enveloping the same, said mass of insulating material being provided with an annular flange projecting a little distance from the general equatorial plane of said mass of insulating material, and further provided with a larger flange of annular form concentric to said first-mentioned flange and extending a greater distance than the same from said general equatorial plane.

20 9. A disk strain insulator, comprising suspension members, a mass of insulating material partially enveloping the same, said mass being provided centrally with a disk integral therewith and lying substantially in the general equatorial plane of said mass, and further provided with flanges extending in opposite directions from said equatorial plane.

25 10. A disk strain insulator, comprising

suspension members, a mass of insulating material partially enveloping the same and having a disk portion, said disk portion being provided with annular collars extending in opposite directions and in the general direction of said suspension members. 30

35 11. A disk strain insulator, comprising strain members, a body of insulating material partially enveloping the same and having a comparatively large disk, said disk being provided with collars integral therewith and extending in opposite directions. 40

12. An insulator, comprising a hollow member provided with a bottom and further provided with an opening in said bottom and with slots merging into said opening, a bolt 45 provided with a stem extending through said opening and with an enlarged portion disposed within said hollow member, and insulating material disposed intermediate said enlarged portion and said hollow member. 50

In testimony whereof I have signed my name to this specification in the presence of two subscribing witnesses.

LOUIS STEINBERGER.
